UNITED STATES PATENT OFFICE

MARION R. HAMRE, OF BROOKLYN, NEW YORK

DESIGN FOR A PILLOW COVER OR THE LIKE

Application filed January 3, 1933. Serial No. 46,679. Term of patent 3½ years.

To all whom it may concern:

Be it known that I, MARION R. HAMRE, a citizen of the United States, residing in the borough of Brooklyn, city of New York, county of Kings, and State of New York, have invented a new, original, and ornamental Design for a Pillow Cover or the like, of which the following is a specification, reference being had to the accompanying drawing forming part thereof.

The figure is a plan view of a pillow cover or the like showing my new design. The dot and dash lines on the drawing outline the design unit covering a quarter of the design area comprising a corner thereof. It is understood that this unit is repeated in regular succession in the remaining corner squares of the pillow cover.

I claim:

The ornamental design for a pillow cover or the like substantially as shown, and described.

MARION R. HAMRE.
